(57) **CLAIM**

The ornamental design for a canning tool set as shown and described.

DESCRIPTION

FIG. 1 is a top perspective view of a canning tool set, shown in a reduced scale, showing my new design;

FIG. 2 is a top perspective view thereof, shown without the canning jar clamp and the funnel for clarity of disclosure; FIG. 3 is a bottom perspective view thereof, shown without the canning jar clamp and the funnel for clarity of disclosure; FIG. 4 is a front view thereof, shown without the canning jar clamp and the funnel for clarity of disclosure;

FIG. 5 is a rear view thereof, shown without the canning jar clamp and the funnel for clarity of disclosure;

FIG. 6 is a left side view thereof, shown without the canning jar clamp and the funnel for clarity of disclosure;

FIG. 7 is a right side view thereof, shown without the canning jar clamp and the funnel for clarity of disclosure; FIG. 8 is an enlarged top plan view thereof, shown without the canning jar clamp and the funnel for clarity of disclosure;

FIG. 9 is an enlarged bottom plan view thereof, shown without the canning jar clamp and the funnel for clarity of disclosure;

FIG. 10 is a top perspective view thereof, shown without the bubble remover and the funnel for clarity of disclosure;

FIG. 11 is a bottom perspective view thereof, shown without the bubble remover and the funnel for clarity of disclosure; FIG. 12 is a front view thereof, shown without the bubble remover and the funnel for clarity of disclosure;

FIG. 13 is a rear view thereof, shown without the bubble remover and the funnel for clarity of disclosure;

FIG. 14 is a left side view thereof, shown without the bubble remover and the funnel for clarity of disclosure;

FIG. 15 is a right side view thereof, shown without the bubble remover and the funnel for clarity of disclosure;

FIG. 16 is a top plan view thereof, shown without the bubble remover and the funnel for clarity of disclosure;

FIG. 17 is a bottom view thereof, shown without the bubble remover and the funnel for clarity of disclosure;

(Continued)

FIG. 18 is a top perspective view thereof, shown without the bubble remover and the canning jar clamp for clarity of disclosure;

FIG. 19 is a bottom perspective view thereof, shown without the bubble remover and the canning jar clamp for clarity of disclosure;

FIG. 20 is a front view thereof, shown without the bubble remover and the canning jar clamp for clarity of disclosure;

FIG. 21 is a rear view thereof, shown without the bubble remover and the canning jar clamp for clarity of disclosure;

FIG. 22 is a left side view thereof, shown without the bubble remover and the canning jar clamp for clarity of disclosure;

FIG. 23 is a right side view thereof, shown without the bubble remover and the canning jar clamp for clarity of disclosure;

FIG. 24 is a top plan view thereof, shown without the bubble remover and the canning jar clamp for clarity of disclosure; and,

FIG. 25 is a bottom plan view thereof, shown without the bubble remover and the canning jar clamp for clarity of disclosure.

The evenly broken lines illustrate portions of the canning tool set that form no part of the claimed design.
